DRILLING RIG

Forrest J. Young, Los Angeles, Calif., assignor to
 The National Supply Company, Pittsburgh, Pa.,
 a corporation of Pennsylvania

Application December 3, 1945, Serial No. 632,342

20 Claims. (Cl. 254—187)

1

This invention relates to drawworks, and more particularly to equipment for a drilling rig for the drilling of wells.

Drilling rigs as now constructed are commonly powered with internal combustion engines so arranged that the flow of power to the work is directed similarly to that of a steam powered drilling rig; consequently change speed transmissions are now required since the power and speed necessary for each particular operation is not available because the internal combustion engine must be kept operating above a minimum speed because the torque at the power take-off falls greatly at the lower speeds.

Another problem of considerable importance which has faced the industry in the construction, transportation and erection of drilling rigs is brought about by the size of the structures, i. e., the dimensions thereof which have required special equipment and special permits to allow their transportation over highways.

It is therefore an object of this invention to provide a drilling rig which is of the internal combustion engine power type and which incorporates an improved arrangement of sprockets and clutches or transmission elements which will considerably increase the efficiency of this type of drilling rig.

Another object of this invention is to provide a construction of drilling rig which may be of the heavy duty type and which is of unit construction permitting transportation and assembly of the drilling rig in an efficient manner and which is so constructed, and the size of units of which are such, that the same may be transported over highways on existing equipment and without the necessity of obtaining special permits for the use of highways in their transportation.

Another object is to provide a portable power unit having a plurality of engine assemblies positioned transversely thereof in parallel relation, and power compounding clutch means mounted between the prime movers, whereby the power unit may be of minimum width.

Another object of this invention is to provide a drilling rig including a hoisting means which is capable of being driven at top speed for quickly raising the elevators and traveling block to the top of the drilling pipe stands and which is so constructed as to have immediately available the speed which will permit operation of the rig at the required power to lift the heavy drilling string whereby the drill string supporting means or slips may be withdrawn allowing the drill pipe to be lowered.

2

Another object of this invention is to provide in a drilling rig means for rotating a catshaft which carries a joint breaker type cathead operated for the purpose of breaking loose the joints in the drill string at a speed relatively slow while still retaining the hoist drum transmission drive operative to drive the hoist at the speed required for the load of the drill pipe, that is, either at high, intermediate or low speeds.

10 Another object of this invention is to provide a drilling rig having a spooling drum and a source of power with a change-speed transmission interposed therebetween to drive the drum at a plurality of speeds and having a power take-off element for driving a driven mechanism, the element associated with the change speed transmission adapted to be driven directly from one of the transmission drive means for rotation independently of the speed of drive to the spooling drum.

15 Another object of this invention is to provide a drilling rig which is operable even though subjected to heavy loads, as in the lining of the well with casing, which will permit the raising of the empty traveling blocks at high speed while retaining a transmission connection to the drum such as will permit the drum to operate efficiently for the heavy lifting of the drill string when desired.

20 Another object of this invention is to provide a rotary drilling rig which includes multiple speed transmission means capable of maintaining higher or lower speed of selective connections to the hoisting drum so that the high speed is immediately available for raising the empty traveling block without disturbing the selected speed required for carrying on other operations in the drilling rig.

25 Another object of this invention is to provide a drilling rig including a transmission means in which the flow of power is divided at a shaft, one side of which is connected with the hoisting drum and the other side of which may be connected to the rotary machine, which makes possible the inclusion in the drilling rig of a four-speed forward and one speed reverse transmission for the hoisting drum, and including an extra high speed for operation of the empty traveling blocks.

30 It is a further object of this invention to provide a rotary drilling rig including means for dividing the flow of power as hereinabove set forth and which likewise includes means which permit of utilization of a transmission providing for rotary drive speeds and a low and high speed cathead drive.

3

Other objects and advantages of this invention, it is believed, will be apparent from the following detailed description of a preferred embodiment thereof as illustrated in the accompanying drawings.

In the drawings:

Figure 1 is a divided plan view of a drilling rig embodying my invention with the drawing divided between the drawworks unit and the power unit.

Figure 2 is a side elevation of the portion of the drilling rig illustrated in Figure 1, including the first power engine.

Figure 3 is an enlarged plan principally in section of the change speed transmission unit including the input shaft and jackshaft as embodied in the drawworks.

Figure 4 is a plan principally in section showing the divided lineshaft construction employed in this drawworks.

Figure 5 is an exploded view of the clutch construction employed for joining the sections of the divided lineshaft.

Figure 6 is a plan principally in horizontal section of the hoisting drum and shaft including the rotary drive means.

In the preferred embodiment of my invention illustrated in the accompanying drawings, I have illustrated a drilling rig developed to provide three essential units comprising the drawworks unit A, a power unit B and rotary machine C. In order to permit these units to be transported over the highways, the regulations of most states require that their maximum width be not in excess of 8 feet. In the development of the drawworks unit A for use in drilling a 10,000 foot well, the overall dimensions of the hoisting drum 1, the shaft bearings for supporting the same, the brake rims 2 and 3 thereof, are such that the remaining space within the eight foot limit will permit only a single transmission drive as provided by the sprocket 4 which is secured to the drum shaft 5 upon which the drum 1 is mounted.

In the operations performed by such a drilling rig, it is essential to provide a multiple speed drive for the drum 1, a multiple speed drive for the rotary machine C, and to provide a high and low speed drive for the catshaft 6 of the drilling rig.

A drilling rig of this type is employed for hoisting the drill pipe out of the hole, in which operation the drawworks unit A serves as a hoist to lift the pipe at varying speeds and it further provides a means for rotating the catshaft 6. The catshaft 6 carries a "breaker type" cathead at one end which is used to break the joint in the drill pipe, and the drawworks A further provides means for turning the rotary machine C for unscrewing the drill pipe joints.

Also in the operation of "coming out of the hole" it is highly desirable to "break" the tool joints or casing joints with a constant low speed cathead drive and this is desirable irrespective of the transmission speed of the hoisting drum. In other words, the hoisting operations due to the varying loads require different speeds while the catshaft should operate at a constant low speed. Conversely, for the operations of "going in the hole" as the weight of the unloaded blocks, hook and line do not vary, and since it is desired to raise the empty blocks as quickly as possible, it is therefore desirable to have available in the drawworks a constant high speed for the hoisting drum which may be then used for raising the empty blocks and as it is necessary to lift the drill pipe slowly for releasing the rotary machine slips, to

4

have a constant low hoisting speed readily available.

During these same operations as there is no variance required in the speed necessary for operation of the catshaft in the spinning up of the drill pipe with the spinning line or for the tonging of the joints with the tong line, it is desirable to have a constant catshaft speed.

In the operation of going in the hole, the drawworks unit is used for lowering the pipe in the hole and is also provided with a means as is herein specifically illustrated for quickly raising the empty traveling block to the position in the derrick where they may be used for attachment to a further stand of drill pipe. The drawworks unit also provides means which are readily available to lift the heavy drill string after the new stand of pipe has been connected thereto so that the slips of the rotary machine may be released, permitting the drill pipe to be lowered.

Combined with these requirements, in the operation of "going in the hole" is another requirement that the drawworks unit should include a means to rotate the catshaft at a high speed suitable for spinning up the drill pipe when the new stand thereof is threaded to the portion of the drill string supported by the rotary table, and this means should also be available for "tonging" the joints. The drill string stands which are added to the drill string in the lowering operation are approximately 90 feet in length and it is essential to the efficient operation of the drilling rig that the cycle of handling this drill stand in either direction be accomplished in approximately 50 to 60 seconds. This places a requirement upon the drilling rig that means should be provided of simple quick-acting controls so that any one of the functions described may be done very quickly and that the shifting from one operation to another may be made in a minimum of time.

The third operation, i. e., the actual drilling, is where the drill bit is supported by the drill string on the bottom of the hole. In order to properly carry out the drilling operations under different conditions of drilling or for reaming the hole, depending in many instances upon the type of formation encountered, it is required that the rotary machine be driven at a multiplicity of speeds enabling the selection of the speed at which the bit will most effectively operate in the type of formations encountered. As the rotary drawworks employed in such a drilling rig ordinarily includes multiple speed transmission for the purpose of driving the hoisting drum at a plurality of speeds, this multiple speed transmission is also utilized to drive the rotary machine. During the operation of drilling it is a further requirement that the drawworks be so arranged that the drill pipe may be readily lifted at any time and that the drawworks be so operated as to enable the imposition of the required pressure upon the drill bit by supporting the load thereof on the line reeved upon the drilling drum and which passes over the crown block and is connected to the traveling block. This operation is well understood in the art so it is not deemed essential to specifically illustrate the reeving of the supporting cable or the crown block of the derrick or traveling block by which the drill string is supported.

The fourth operation required of such drilling rig is the handling of the casing. In the operation of drilling a well it usually becomes necessary to "set" one or more "strings" of casing in order to case the hole being drilled. In this operation

it is required that the drawworks be capable of lifting very heavy loads. A primary requirement of the drawworks during this operation is that it be capable of operation at selected speeds required for the extremely heavy loads and to quickly lift the empty blocks and lastly that it be provided with a fairly fast catshaft so that the cathead speed will be suitable for both "spinning up" and "tonging up" the casing threads.

The drilling rig embodying my invention so combines the power unit, the drawworks unit and the rotary machine as to enable full attainment of the foregoing requirements. A further characteristic of the drilling rig embodying my invention is that it employs as the medium of power internal combustion engines which provide the power for driving the drilling rig and the rotary machine, and the engines are united in a unitary assembly of a maximum of 8 feet width so that this unit is likewise transportable over highways within the regulation requirements.

The drawworks unit A comprises essentially the drum 1 and its supporting shaft 5 which is driven from the line shaft 7. The line shaft 7 is in turn driven by a jackshaft 8. The jackshaft in turn is driven from the input shaft 9. In addition to this transmission means the drawworks unit includes the drive unit 10 through the medium of which the rotary machine C is driven.

Carried by the drawworks frame 11 in which the aforesaid shafts are supported is the catshaft 6. Likewise supported upon the frame may be the sand reel shaft 12 upon which the sand reel 13 is secured. A fluid brake unit 14 may be coupled with the lineshaft 7 so as to provide a braking unit for this shaft.

The input shaft 9 of the drawworks unit A is driven from the power unit B which includes a pair of internal combustion engines 21 and 22. These engines are mounted in parallel relation transversely of the base frame 16 and are adapted to drive parallel stub-shafts 24 and 29, each provided with an outboard bearing 23 and 30 carried on the base frame 16. Carried by the shaft 24 and fixed thereon is a multiple chain sprocket 19 aligned with a driven sprocket 20 associated with the power input shaft 9. A multiple strand chain 18 is trained over the sprockets 19 and 20. Also fixed on the shaft 24 is a compounding sprocket 25 aligned with sprocket 26 which is rotatably mounted on the clutch shaft 34. A multiple strand chain 17 is trained over sprockets 25 and 26.

The clutch shaft 34 is carried on the base frame 16 between the engines 21 and 22 and is parallel to the shafts 24 and 29. A friction clutch 43 is provided for selectively coupling the sprocket 26 in driving relation with the clutch shaft 34. A sprocket 33 is fixed upon the clutch shaft 34 and is operatively connected by chain 32 to a sprocket 31 fixed on the shaft 29. The reason for the provision of the clutch shaft 34, together with its associated sprockets 26 and 33 and friction clutch 43, and its location between the engines 21 and 22, is to eliminate the need for clutches on the stub shafts 24 and 29. By this means the overall length of the engine assemblies including the stub shafts and bearings can be held within the 8-foot limit.

As a further means of reducing the overall length of the engine assemblies, the cooling radiators 35 and 36 for the water cooling circulatory systems of the internal combustion engines 21 and 22 are displaced with reference to the engine locations and are mounted upon the rear of the

base frame 16. The fan elements (not shown) of these radiators are driven by belted connections 39 and 40 from pulleys rotatably mounted on the countershaft 38, and provided with individual clutches 41 and 42. The countershaft 38 is rotatably mounted on the base frame 16 and is driven by fixed sprockets 27, 28 and the chain 37. An air compressor unit 15 is driven from the countershaft 38 to provide a supply of air under pressure for operating the pneumatic friction clutches described hereinafter, and for starting the engines 21 and 22, and for other purposes.

In order to attain the flexibility of drive to meet the requirements as hereinbefore specified, the drawworks unit embodying my invention has the following characteristics:

A frame is provided which may comprise spaced frame plates 44 which are secured to a base plate 45. The drumshaft 5 is journalled in bearings 5^a carried by the frame plates 44 and the drum 1 is suitably secured to the shaft 5. The drum 1 has brake flanges 46 at its opposed ends and the brake rims 2 and 3 are suitably secured to these flanges.

The input shaft 9 is supported in bearings 47 which are supported in frame plates 48 offset inwardly with respect to the frame plates 44 and likewise mounted upon the base plate 45. Power is transmitted to the power input shaft 9 through the sprocket 20 from engine extension shaft 24. The sprocket 20 is formed as an integral portion of the clutch housing 49 of a friction type pneumatic clutch 50. The clutch 50 is mounted upon the overhanging end 35 of the input shaft 9 and provides means for releasably clutching the sprocket 20 to the input shaft 9.

The clutch mechanism generally designated 50 includes a spider 51 secured on the outboard end 40 of the power input shaft 9. This spider 51 has the sprocket 52 and cylindrical extension 53 formed integrally therewith, and the extension 53 has a series of external spline teeth 54 formed thereon. The clutch housing 49 has the driven sprocket 20 formed on its outer rim. The housing 49 includes the end wall 55 which is bolted at 56 to the inner sleeve 57 which is rotatably supported upon axially spaced bearings 58 and 59. A cover 65 is secured by bolts (not shown) to the end wall 55. In effect, therefore, the clutch housing 49 (including the end wall 55, cover 65, and the sleeve 57) is rotatably mounted with respect to the shaft 9 and the spider 51.

Clutch plates 60 and 61 are carried by the housing 49 and cylindrical spider extension 53 respectively and provide friction plates for the clutch. The inner of the clutch plates 60 is provided with trunnions 62 which engage the annular piston 63 which is positioned within the annulus 64 formed in the cover 65. Fluid under pressure is introduced into the annulus 64 and acts to urge the ring 63 outwardly therefrom to move the clutch plates 60 into frictional contact with the clutch plates 61. Means are provided for admitting fluid under pressure into the ducts 66 of the cover 65, which means may be of any suitable or desirable construction. As the cover 65 is rotating with the housing 49 of the clutch 50, a collar ring 67 is mounted upon the ported trunnion 68 to provide a means of carrying the fluid under pressure from the supply conduit 69 to the ducts 66.

In order to provide a multiple speed and reverse drive from the input shaft 9 to the jackshaft 8, I provide a pair of spaced sprockets 70

and 71, which are journaled on suitable bearings 72 and 73 upon the input shaft 9. Positioned between these sprockets and secured to the input shaft 9 is a clutch collar 74 upon which there is positioned a clutch ring 75 adapted to be shifted axially of the shaft 9 by means of a shifter mechanism diagrammatically indicated at 76.

The clutch ring 75 has internal clutch teeth adapted to be selectively engaged with the clutch teeth 77 and 78, respectively, formed upon the hubs of the sprockets 70 and 71, respectively. Likewise mounted upon the input shaft 9 and secured thereto to rotate therewith is a reverse gear 79 which meshes with a reverse gear 80 journaled upon the jack shaft 8. A brake wheel 81 is secured to the outboard end of the input shaft 9 and a brake band 82 is mounted upon the brake wheel 81 and suitable means are provided for tightening and releasing the brake band 82 from the brake wheel 81.

Secured to the input shaft 9 is a low speed sprocket 83 which is in line with the low speed sprocket 84 which is journaled upon the jack shaft 8. The transmission drive from the input shaft 9 to the jackshaft 8 provides a four speed forward and one speed reverse drive.

The low speed is accomplished by means of the chain between sprockets 83 and 84. The second speed drive is between the second speed sprocket 52 and the sprocket 85 journaled on the jackshaft 8. A double sprocket 86 is secured on the jackshaft 8 and provides two multiple chain sprockets 87 and 88 which are in position of alignment with the sprockets 71 and 70, respectively, of the input shaft 9. The high speed drive is provided by a chain trained between the sprockets 71 and 87, and the third speed drive is provided by a chain connecting the sprockets 70 and 88. The jackshaft is journaled on bearings 89 and 90 positioned in the left side frame plate 48 and the right frame plate 44.

The transmission connections provided between the jackshaft 8 and the line shaft 7 (Figure 4) in conjunction with the multiple speed and reverse drives from the input shaft 9 to the jackshaft 8 enable the carrying out of the after-described operations.

In order to enable these operations to be carried out, the line shaft is divided into two aligned sections which may be defined as the drum drive section of the line shaft 7^a and the rotary table drive section of the line shaft 7^b. The two sections of the line shaft are supported on suitable bearings as will hereinafter be described and are adapted to be releasably coupled together by means of a spline clutch 91 actuated by means of a suitable collar 92 when desired.

The low speed sprocket 84 is journaled on the jackshaft 8 on bearings 93 and supported on the hub 94 are clutch rings 95 and 96 which are adapted to be shifted by shifting collars 97 and 98, respectively, into clutching engagement with the clutch teeth 99 of the double sprocket 86 and clutch teeth 100 carried by the hub of the catshaft drive sprocket 101. A chain is trained over the sprocket 101 and over the driven sprocket 102 secured to the catshaft 6. The catshaft drive sprocket 101 is journaled on the jackshaft 8 on suitable bearings and its hub portion is formed with a clutch ring 103 adapted to be selectively engaged with the clutch teeth of a clutch collar 104 mounted within the sprocket

85 and also within the sprocket 105 which forms the high speed line shaft drive sprocket.

A shifter ring 106 is splined upon the hub of the sprocket 105 and is connected with the clutch ring 104 by means of a plurality of connecting bolts 107. A suitable collar 108 is provided for shifting the ring 106. The sprockets 101 and 105 are welded together at 152 to form an integral double sprocket member 110 which is supported on axially spaced bearings 109. Suitable spline teeth are provided on the double sprocket member 110, collar 104, sprocket 85 and collar 111 which is keyed to the shaft 8, to enable the clutch collar 104 to connect the sprockets 85 and 105 for dependent rotation, or to connect the double sprocket member 110 directly to the shaft 8. In Figure 3 the clutch collar 104 is shown in neutral position in which neither of these drives is operative.

Secured to the jackshaft 8 near one end is a drive collar 112 adapted to be releasably engaged by the shiftable collar 113 with the sprocket 85, which is rotatably supported on bearings 85^a. A clutch 114 is provided for releasably clutching the reverse drive gear 80 to the double sprocket 86 when desired. The reverse drive gear 80 is journaled upon jackshaft 8 upon suitable bearings 115. Secured to the overhanging end of the jackshaft 8 is a low speed drive collar 116 which is adapted to be releasably clutched through the medium of the clutch 117 to the low speed line shaft drive sprocket 118 which is journaled upon the outer overhanging end of the jackshaft 8 upon suitable bearings 119. Sprockets 118 and 105 provide means for driving the respective sections of the lineshaft 7^a and 7^b and as the shaft 8 can be driven in a reverse direction and coupled with either of the drive sprockets 118 or 105, or with the catshaft drive sprocket 101, when desired, any one of these drives may be in a forward or reverse direction. The low speed jackshaft drive sprocket 118 drives the low speed line shaft sprocket 120. The sprocket 120 is formed upon the housing 121 of the pneumatic clutch 122. Clutch 122 is similar in all respects to the pneumatic clutch 50 so that it is not believed essential to describe in detail the structure of this clutch, the function of which is to releasably clutch the sprocket 120 to the drum drive section 7^a of the line shaft and to the drum shaft drive sprocket 123 which is formed integral with the spider 124 of the clutch 122.

The spider 124 is secured to the drum shaft drive section 7^a of the line shaft. Section 7^b of the line shaft is adapted to be driven by a chain which connects the jackshaft sprocket 105 with the line shaft high speed drive sprocket 125. The sprocket 125 is formed on the hub of a spider 126 of the pneumatic clutch of the high speed drum shaft drive clutch 127. This clutch 127 is likewise a pneumatic clutch and is similar in construction to the pneumatic clutch 50 with the exception that in this case the internal spider 126 is journaled on suitable bearings 128 upon the line shaft 7 and the external member or housing 129 of the clutch is secured to the overhanging end of the rotary drive section of the line shaft 7.

The line shaft sections are supported by pedestal bearings 130 and 131, pedestals for which are supported upon the base plate 45. The housing 129 of the pneumatic clutch 127 carries clutch teeth 132 which permits the same to be clutched to the brake shaft 133 of a hydraulic brake commonly referred to in this art as a hy-

dromatic brake 134 which is supported within a frame 135 adapted to be secured to the draw-works frame plate 44. The clutch 127 may be of the type shown in detail in my co-pending application, Serial No. 700,260, filed September 30, 1946, now abandoned.

Means are carried on the rotary drive end 7^b of the line shaft 7 which provide one element of the drive for the rotary machine C. Secured to the end flange of the section 7^b of the line shaft is an end cap 136 which is formed to provide the rotary machine line shaft drive sprocket 137. The end cap 136 is secured to the end flange of section 7^b of the line shaft by means of suitable bolts 138 and dowels 138^a. Secured to the adjacent end flange of the drum shaft section 7^a of the line shaft 7 is a connecting collar 139 which is secured in position by means of bolts 140 and dowels 140^a. Formed on the periphery of the end cap 136 and collar 139 are spline teeth which are adapted to be selectively engaged with the internal spline teeth of a clutch ring 91, which is actuated by the collar 92.

A rotary machine countershaft 141 is journaled in suitable bearings 142 upon the base plate 45. Journaled upon the shaft 141 is a sprocket 143 which is driven by means of a chain from the sprocket 137. A clutch 144 is provided for releasably clutching the sprocket 143 to the countershaft 141. Secured to the countershaft 141 is a bevel pinion 145 which meshes with a bevel gear 146 secured to the end of the rotary machine drive shaft 147. The shaft 147 is supported in bearings 148 and 149 supported upon the base plate 45 of the drawworks. The rotary machine drive shaft 150 is coupled with the shaft 147 by means of a suitable coupling 151.

The single drive from the line shaft 7 to the drum shaft 5 is provided by the sprocket 123 which drives the drumshaft drive sprocket 4 through the medium of a suitable chain.

Suitable controls are diagrammatically indicated in the driller's position at 152 (Figure 2) for controlling the operation of the engines 21 and 22 and clutches 122 and 127, and the clutches of the multiple speed transmission as hereinabove described.

The operation of the drilling rig in order to carry out the aforeslated objects of my invention is:

In the operation of "going into the hole," that is, lowering the drill pipe into the hole being drilled, the requirement is of a high speed of rotation of the drum 1 to lift the empty blocks at a high rate of speed to a position where they will pick up a stand of drill pipe so that it may be positioned over the hole and then threaded to the portion of the drill string then supported in the well hole. When so positioned, it is desirable to have a cathead which will spin the pipe at a high speed to screw the stand of pipe picked up to the said drill string. After the stand has been connected to the drill pipe, it is necessary to have a low speed available for the drum for the lifting of the heavy drill string so that the supporting slips carried in the rotary machine C can be released to permit the lowering of the drill string with the new stand into the well. The particular requirements of this operation are therefore of a simultaneous need for a fast drive to the drum and a fast drive to the cathead. These requirements are met in the drilling rig embodying my invention as follows:

The high speed drive to the catshaft is provided by the drive from the sprocket 52 to the

sprocket 85, hence to the sprocket 105 by engagement of the clutch 104 and as the catshaft sprocket 101 is attached integrally to the sprocket 105 by any suitable means such as welds 152, the sprocket 101 will be driven at the high speed accomplished through this transmission. As the sprocket 101 is connected by the chain directly to the sprocket 102 carried upon the catshaft 6, the high speed will be transmitted to the spinning head 153 of the catshaft 6.

The differential speeds for operation of the drum 1 are provided as follows: The low speed requirement is provided by driving the drum drive section 7^a of the line shaft 7 through the transmission connections provided by the sprocket 83 on the input shaft 9 which operates to drive the sprocket 84 on the jackshaft 8, which shaft is in turn rotated at the low speed by engagement of the clutch 95 with the clutch teeth 99 of the sprocket 86 and by engaging the clutch 117 with the drive collar 116 so that the sprocket 118 is driven with the jackshaft 8.

The pneumatic clutch 122 positioned on the drum shaft section 7^a of the line shaft is engaged so that on rotation of the clutch housing 121 by the chain connected with the sprocket 118, the multiple chain drive of the sprocket 123 acts to drive the drum shaft sprocket 4 of the drum shaft 5 at the low speed required for lifting the heavy load of the drill pipe.

The high speed for raising the unloaded traveling block is instantly available through sprocket 125, pneumatic clutch 127, section 7^b of the line shaft, clutch 91, section 7^a of the line shaft, and sprocket 123. The pneumatic clutch 122 is released to disconnect the drive from sprocket 120 to section 7^a of the line shaft. Thus, there is coincidentally available the two relatively high speed drives for the drum and the catshaft together with the easily available low speed drive required for lifting the pipe to release the pipe supporting slips in the rotary machine C.

In the operation of coming out of the hole there is a different requirement of availability of speeds for carrying on the required operations in that it is highly desirable that the cathead shaft 6 be driven slowly so that the "break" head or spool 154 of the catshaft will be rotated slowly for the purpose of breaking the threaded joint between the stand of drill pipe being removed from the drill pipe. At the same time it is essential to have a low speed drive for operating the rotary machine for the purpose of unscrewing the joints between the drill pipe and the respective stands thereof.

During this operation it is a requirement that all speeds of operation be available for driving the hoisting drum 1 carried by the drumshaft 5 so that the maximum speed of operation can be obtained to remove the drill pipe from the hole depending upon the weight of the drill pipe as it is progressively reduced in length by the removal of the stands therefrom. In accordance with my invention, these essential requirements are met as follows:

The catshaft 6 is driven slowly through the transmission connections provided from the power input shaft 9 by sprocket 83 acting through its chain connection to drive the sprocket 84 which is then connected with the catshaft drive sprocket 101 by shifting the clutch shifter 98 into position to engage the clutch teeth 96 with the teeth 100 carried by the sprocket 101. Driving sprocket 101 simultaneously results in driving the sprocket 105 at the slow speed and by closing the pneumatic

clutch 127, the rotary machine drive section 7^b of the lineshaft 7 is driven at the low speed. The rotary machine is then driven by the sprocket 137 acting to drive the sprocket 143 and upon closing of the clutch 144, the countershaft 141 is driven at the low speed required for the operation of the rotary machine. Due to the divided arrangement of the lineshaft 7 all of the available speeds for operating the drum 1 are available to drive the drum 1 at any of the required speeds. Thus, the jackshaft may be driven at the low speed by closing of the clutch 97 for the sprocket 84 into engagement with the clutch teeth 99 on the sprocket 86, or this clutch may be disengaged and the jackshaft 8 may be rotated at the second available speed provided by the chain from the sprocket 52 to the sprocket 85 during which time the clutch 104 is disengaged and the clutch 113 is engaged.

The third speed of drive is provided by shifting the clutch 75 into position of engagement of the teeth 77 of the sprocket 70 so that the double sprocket 86 is driven thereby driving the jackshaft 8. In this drive, of course, the clutches 97 and 113 are disengaged. The highest speed drive for the drum 1 is likewise available by shifting the clutch 75 out of engagement with clutch teeth 77 and to engagement with the clutch teeth 78 of the sprocket 71 which then drives the sprocket 87 by the chain connected with the sprocket 71. During any of these drives the clutch 117 is engaged so that the sprocket 148 is rotated with the jackshaft 8.

Clutch 122 is also engaged so that the drive of the sprocket 120 at the selected speed will result in driving the sprocket 123 of the pneumatic clutch 122 at the selected speed.

It will be appreciated that in this operation when a stand of pipe is removed from the drill pipe supported in the rotary machine C that the desired speed of operation of the drum 1, i.e., the highest speed thereof, will be available if desired, for lifting this stand to its position in the well derrick. At the same time by the simple action of manipulating the respective clutches, the speed of operation of the drum 1 will be available which is best suited under the power delivered from the engines 21 and 22 or 21 or 22 for raising the drill pipe from the well to the height required for elevating stands thereof to a position above the rotary machine C so that they may be removed upon setting the slips up in the rotary machine to support the drill pipe in the well. When thus raised, the breaker line from the breaking spool 154 of the catshaft 6 may be actuated at the slow speed required to "break" the joint between the stand and the drill pipe. It will also be apparent that through the transmissions provided from the power input shaft 9 to the drum drive section 7^a of the line shaft 7 that all four speeds forward and the speed of drive in reverse are available for driving the drum shaft depending upon the clutch settings.

Having fully described my invention, it is to be understood that I do not wish to be limited to the details herein set forth, but my invention is of the full scope of the appended claims.

I claim:

1. In a consolidated rig, a drawworks comprising a frame of a width sufficient to accommodate a drumshaft with a drum supported thereon and a single drive to the drumshaft, a line shaft carried by the frame and providing a single transmission connection to the drumshaft for driving the same, the line shaft being selectively divided

to provide an independent drive section, means for selectively clutching the two sections together, axially spaced bearings for independently supporting the two line shaft sections, a jackshaft supported in the frame, a drive member on the jackshaft and adapted to be selectively engaged in driving relation therewith, a transmission connection from the jackshaft to the drumshaft drive section of the line shaft, a transmission drive connection from the drive member to the independent drive section of the line shaft, means driven from the independent drive section selectively operable to drive a driven mechanism, and means for driving the jackshaft at a plurality of selected speeds.

2. In a rotary drawworks, the combination of a frame, a drumshaft rotatably supported within the frame, a line shaft supported to the rear of the drumshaft, a jackshaft supported in the frame to the rear of the line shaft, and a power input shaft supported in the frame to the rear of the jackshaft, means providing a selective multiple speed and reverse drive from the power input shaft to the jackshaft, a drive member on the jackshaft and adapted to be driven independently thereof, the line shaft being divided into two axially disposed independent sections, means for selectively driving the first of the line shaft sections at a plurality of speeds from the jackshaft, means for driving the second section of the line shaft from the drive member at a plurality of forward speeds and reverse, means for driving the drumshaft from the first section of the line shaft, and power take-off drive means operatively associated with the second section of the line shaft.

3. In a consolidated rig, the combination of a frame of predetermined width sufficient to accommodate therewithin a hoisting drum upon a drumshaft and a single drive means for the drumshaft, a line shaft supported to the rear of the drumshaft, a single sprocket and chain drive from the line shaft to the drumshaft, the line shaft being divided into independently rotatably axially aligned sections, axially spaced bearings for independently supporting the two line shaft sections, clutch means for selectively clutching the line shaft sections together so that they may rotate as a unit, a jackshaft positioned to the rear of the line shaft, drive members on the jackshaft, clutch means for connecting the drive member with said jackshaft, sprocket and chain drive means from the drive members to each section of the line shaft whereby the said sections of the line shaft may be simultaneously driven at differential speeds, and means whereby the jackshaft may be driven at a plurality of forward speeds and reverse.

4. In a rotary drawworks, the combination of a drumshaft, a drum supported upon the drumshaft, a line shaft positioned to the rear of the drumshaft, means for driving the drumshaft from the line shaft, the line shaft being divided into two axially aligned independently rotatable sections, clutch means for selectively clutching the line shaft sections together so that they may rotate as a unit, a jackshaft, drive members on the jackshaft, means for rotating one of the drive members independently of the jackshaft, means including clutch means on the jackshaft for driving the two sections of the line shaft from the drive members simultaneously at different speeds, a power input shaft, and a plurality of chain and sprocket transmission connections between the power input shaft and the jackshaft

whereby the jackshaft may be driven from the power input shaft at a plurality of forward speeds and reverse.

5. In a rotary drawworks, the combination of a drumshaft, a hoisting drum supported upon the drumshaft, a line shaft, means for driving the drum shaft from the line shaft, a jackshaft, means for driving the line shaft from the jackshaft at a plurality of speeds, a catshaft drive sprocket supported upon the jackshaft, a catshaft, a sprocket supported upon the catshaft, a chain connecting the latter said sprockets, a driven sprocket journaled on the jackshaft, a pair of clutch means operatively associated with the latter said sprocket and adapted to selectively clutch the said sprocket with the jackshaft and with the catshaft drive sprocket.

6. In a drawworks, the combination of a drumshaft having a spooling drum fixed thereon, a driven sprocket fixed on the drumshaft, a lineshaft divided into two axially aligned and independently rotatable sections, axially spaced bearings for independently supporting the two line shaft sections, releasable clutch means for selectively clutching the lineshaft sections together so that they may rotate as a unit, a drum drive sprocket fixed on the first lineshaft section, a chain operatively connecting the sprockets, means for driving a driven mechanism including a power takeoff sprocket fixed on the second lineshaft section, first and second driven sprockets rotatably mounted on the first and second lineshaft sections, respectively, releasable clutch means for operatively connecting each of the latter said sprockets to its respective lineshaft section, a jackshaft, and separate means on the jackshaft for rotating the first and second driven sprockets.

7. In a drawworks, the combination of a drumshaft, a spooling drum mounted on the drumshaft, a lineshaft divided into two axially aligned independently rotatable sections, axially spaced bearings for independently supporting the two lineshaft sections, releasable clutch means for selectively clutching the lineshaft sections together so that they may rotate as a unit, a drum drive element on the first lineshaft section, transmission connections whereby the drum drive element may drive the drum, a power take-off element on the second lineshaft section, a jackshaft, a first drive member on the jackshaft, transmission connections including a releasable clutch whereby the first drive member may drive said drum drive element, a second drive member on the jackshaft, and transmission connections including a releasable clutch whereby the second drive member may drive the power take-off element.

8. In a drawworks, the combination of a drumshaft having a spooling drum thereon, a lineshaft divided into two axially aligned and independently rotatable sections, axially spaced bearings for independently supporting the two line shaft sections, releasable clutch means for selectively clutching the lineshaft sections together so that they may rotate as a unit, a drum drive sprocket on the first lineshaft section, transmission connections whereby the drum drive sprocket may drive the drum, a power take-off element on the second lineshaft section, a change speed transmission, direct drive means including a releasable clutch for driving the drum drive sprocket forwardly at one speed from the change speed transmission, and indirect drive means including a releasable transmission connection be-

tween the change speed transmission and the second lineshaft section for driving the drum drive sprocket forwardly at another speed.

9. In a drawworks, the combination of a drumshaft having a spooling drum thereon, a lineshaft having a pair of drive elements thereon, the first of said drive elements being operatively connected to drive the drum, the second drive element being operatively connected to drive a power take-off sprocket for a driven mechanism, a change speed transmission, means including releasable clutch means whereby said drive elements may be separately driven simultaneously in the same direction from said transmission at different speeds, a power absorbing brake unit adjacent one end of the lineshaft, and releasable clutch means operatively connecting said brake unit to the drum drive element.

10. In a drawworks, the combination of a drumshaft having a spooling drum thereon, a lineshaft divided into two axially aligned independently rotatable sections, axially spaced bearings for independently supporting the two line shaft sections, releasable clutch means for selectively clutching the lineshaft sections together so that they may rotate as a unit, a drum drive element on the first lineshaft section operatively connected to drive the drum, a power take-off drive element on the second lineshaft section, a power absorbing brake unit releasably connected to the second lineshaft section, and means for rotating the said drive elements.

11. In a drawworks, the combination of a drumshaft, a spooling drum mounted on the drumshaft, a lineshaft divided into two axially aligned independently rotatable sections, releasable clutch means for selectively clutching the lineshaft sections together so that they may rotate as a unit, a drum drive element on the first lineshaft section, transmission connections whereby the drum drive element may drive the drum, a machine drive element on the second lineshaft section, a jackshaft, a catshaft having a cathead thereon, a first drive member on the jackshaft, transmission connections including a releasable clutch whereby the first drive member may drive said drum drive element, a second drive member on the jackshaft, transmission connections including a releasable clutch whereby the second drive member may drive the machine drive element, and transmission connections whereby the second drive member may drive the catshaft independently of the lineshaft.

12. In a drawworks having a drumshaft provided with a spooling drum, a catshaft having a cathead thereon, and a power take-off sprocket, the combination of: a jackshaft having a drive member thereon, transmission connections including releasable clutch means whereby the drive member may drive the drum, first and second driven sprockets rotatably mounted on the jackshaft, clutch means for releasably connecting either of said driven sprockets in driving relation with the jackshaft, a dual sprocket member rotatably mounted on the jackshaft between said driven sprockets, transmission connections whereby the catshaft may be driven from the dual sprocket member, additional transmission connections whereby the power take-off sprocket may be driven from the dual sprocket member, clutch means for releasably connecting the dual sprocket member with either of said driven sprockets, and means for driving said driven sprockets.

13. In a drawworks having a spooling drum, a

catshaft having a cathead thereon, and a power take-off sprocket adapted to drive a driven mechanism, the combination of: a jackshaft having a drum drive member thereon, transmission connections including releasable clutch means whereby the drive member may drive the drum, a power input shaft, low speed and high speed drive means whereby the input shaft may drive the jackshaft, one of said drive means including a driven sprocket rotatably mounted on the jackshaft, a dual sprocket member rotatably mounted on the jackshaft adjacent the said driven sprocket, clutch means for effecting a releasable driving connection between the dual sprocket member and said driven sprocket, and means operatively connecting the dual sprocket member to drive both the catshaft and said power take-off sprocket.

14. In a drawworks having a spooling drum, a catshaft provided with a cathead, and a power take-off sprocket, the combination of: a jackshaft having a drive member thereon, transmission connections including releasable clutch means whereby the drive member may drive the drum, first and second driven sprockets rotatably mounted on the jackshaft, clutch means for releasably connecting either of said driven sprockets in driving relation with the jackshaft, a dual sprocket member rotatably mounted on the jackshaft between said driven sprockets, releasable clutch means for selectively engaging the dual sprocket member in driving relation with the jackshaft, transmission connections whereby the catshaft may be driven from the dual sprocket member, additional transmission connections whereby the power take-off sprocket may be driven from the dual sprocket member, clutch means for releasably connecting the dual sprocket member with either of said driven sprockets, and means for driving said driven sprockets.

15. In a rotary drilling rig, the combination of a spooling drum, a source of power, a change speed transmission operatively interposed between the source of power and the spooling drum whereby the spooling drum may be driven at a plurality of speeds, the change speed transmission including a driven shaft, a plurality of driven elements on the shaft each adapted to drive the shaft at a different speed, the transmission including releasable clutch means for rendering any one of the elements effective to drive the shaft, one of said elements being rotatably mounted on the shaft, a driving member rotatably mounted on the shaft independently of the latter said element and adapted to drive a driven mechanism, clutch means for selectively engaging the driving member with the shaft, and releasable clutch means for establishing a driving connection between the said driven element and the driving member whereby said element and said member may rotate as a unit independently of the shaft.

16. In a drilling rig, the combination of a spooling drum, a source of power, a change speed transmission operatively interposed between the source of power and the spooling drum whereby the spooling drum may be driven at a plurality of speeds, said change speed transmission including a power input shaft and a jackshaft and including a plurality of drive means for driving the jackshaft from the power input shaft at a plurality of speeds, one of the drive means having a driven sprocket rotatably mounted on the jackshaft and provided with releasable clutch means for engaging the sprocket with the jackshaft, a driving sprocket rotatably mounted on the jack-

shaft independently of said driven sprocket and adapted to drive a driven mechanism, clutch means for selectively connecting the driving sprocket with the jackshaft, and releasable clutch means for establishing a driving connection between the driven sprocket and the driving sprocket whereby the sprockets may rotate as a unit independently of the jackshaft.

17. In a drilling rig, the combination of a power input shaft, a jackshaft parallel thereto, bearings for rotatably supporting the shafts, a spooling drum, a drive sprocket on the jackshaft, transmission connections whereby the drive sprocket may drive the spooling drum, a driving sprocket 15 rotatably mounted on the jackshaft and adapted to drive a driven mechanism, clutch means selectively engaging the driving sprocket with the jackshaft, low speed drive means including a low speed sprocket rotatably mounted on the jackshaft whereby the power input shaft may drive the jackshaft, second speed drive means whereby the power input shaft may drive the jackshaft, releasable clutch means for selectively engaging any one of said drive means, additional clutch 20 means adapted to establish a direct driving connection between the low speed sprocket and the driving sprocket independently of the jackshaft, whereby said sprockets may rotate as a unit, and means whereby the power input shaft may be driven.

18. In a rotary drawworks, the combination of a frame, a drum shaft rotatably supported on the frame and having a spooling drum thereon, a line shaft divided into two axially aligned and independently rotatable sections, axially spaced bearings on the frame for independently supporting each of said line shaft sections, releasable clutch means for connecting the adjacent ends of the line shaft sections, means whereby one of the line shaft sections may drive the drum, said means including a driving sprocket mounted on said line shaft section outboard of its supporting bearings, a driven sprocket mounted coaxially of the driving sprocket, clutch means for connecting the sprockets for dependent rotation, a driven sprocket rotatably mounted on the other line shaft section at a position outboard of the bearings therefor, clutch means for connecting the latter said sprocket to the latter said line shaft section, and means for simultaneously driving the said driven sprockets at different speeds.

19. In a rotary drawworks, the combination of a frame, a drum shaft rotatably supported on the frame and having a spooling drum thereon, a line shaft divided into two axially aligned and independently rotatable sections, axially spaced bearings on the frame for independently supporting each of said line shaft sections, releasable clutch means for connecting the adjacent ends of the line shaft sections, means whereby one of the line shaft sections may drive the drum, said means including a driving sprocket mounted on said line shaft section outboard of its supporting bearings, a driven sprocket mounted coaxially of the driving sprocket, clutch means for connecting the sprockets for dependent rotation, a driven sprocket rotatably mounted on the other line shaft section at a position outboard of the bearings therefor, clutch means for connecting the latter said sprocket to the latter said line shaft section, a power take-off sprocket for driving a driven mechanism, the sprocket being fixed to the end of the latter said line shaft section remote from the latter said clutch means, and means for

simultaneously driving the said driven sprockets at different speeds.

20. In a rotary drawworks, the combination of a drum shaft having a spooling drum thereon, a line shaft assembly, means whereby the line shaft assembly may drive the spooling drum, the line shaft assembly including a shaft element rotatably supported on axially spaced bearings, the shaft element having an overhanging portion outboard of one of the bearings, a driven sprocket rotatably mounted on said outboard portion of the shaft element, a friction clutch assembly mounted on said outboard portion and having a housing fixed with respect to the shaft element, said friction clutch assembly being operative to connect the sprocket in driving relationship with the shaft element, an energy-absorbing brake mounted coaxially of the shaft element, releasable clutch means for directly connecting the clutch housing in driving relationship with the

energy absorbing brake, and means for driving said sprocket.

FORREST J. YOUNG.
